RAILWAY-TRAFFIC-CONTROLLING APPARATUS

Application filed September 30, 1929. Serial No. 396,188.

My invention relates to railway traffic controlling apparatus of the type comprising train carried governing means co-operating with devices located at intervals along the trackway.

I will describe one form of apparatus embodying my invention, and will then point out the novel features thereof in claims.

The accompanying drawing is a diagrammatic view illustrating one form of railway traffic controlling apparatus embodying my invention.

Referring to the drawing, the reference character A designates a train carried receiver comprising two magnetizable cores 1 and 3 located in inductive relation. The core 1 is provided with a winding 2 which is constantly supplied with alternating current from a suitable source, such as an alternator 20 G, and the core 3 is provided with a winding 4 in which an alternating electromotive force is induced by the flux created by the current in winding 2 and linking winding 4.

Associated with the receiver A is a relay 25 device, here shown as a grid glow tube T. The tube T consists of two spaced electrodes 5 and 6 and a grid 7 inclosed in a sealed envelope filled with a suitable medium such as neon gas. If an alternating electromotive force, having a magnitude sufficiently great, is applied across electrodes 5 and 6 of a tube of the type described, the medium surrounding the electrodes becomes conducting and a unidirectional current flows from electrode 5 30 to electrode 6. The critical magnitude of the electromotive force necessary to cause tube T to become conducting, however, is dependent upon the potential and relative polarity of grid 7 with respect to electrode 5, this critical magnitude decreasing as the potential of grid 7 increases when the grid is positive with respect to electrode 5, but increasing as the potential of grid 7 increases when the grid is negative with respect to electrode 5.

45 A relay R is provided with a circuit including its own front contact 12, alternator G, and electrodes 5 and 6 of tube T. Winding 4 of receiver A is connected with electrode 5 and grid 7 of tube T. The parts are so proportioned that the electromotive force which is

induced in winding 4 under normal conditions creates a difference of potential between grid 7 and electrode 5 which renders tube T conducting at the magnitude of the electromotive force impressed across electrodes 5 and 6 by alternator G. Relay R is therefore normally energized over the stick circuit previously described.

55 Relay R may be used to control governing means on the train in any suitable manner. As here shown the relay R controls a magnet valve M which is energized only when relay R is energized and which is arranged to apply the brakes on the train when the valve becomes de-energized.

60 Located in the trackway adjacent the path of travel of the train carried receiver is a controlling element B comprising an inductor 8 provided with a winding 9. The winding 9 is provided with a circuit controlled by 65 a front contact 10 of a relay S. The relay S may be controlled in any suitable manner. For example, relay S may be controlled by traffic conditions in advance in such manner, that when traffic conditions are safe, relay S is energized to close contact 10, but that when traffic conditions are dangerous, relay S is de-energized so that contact 10 is opened.

70 In explaining the operation of the apparatus, I will first assume that when the train passes over the trackway element B, contact 10 of relay S is opened, so that winding 9 is on open circuit. Under these conditions the inductor 8 shunts flux away from the winding 4 so that the magnitude of the 75 electromotive force induced in winding 4 is reduced. As a result, the difference of potential between grid 7 and electrode 5 of tube T is changed to a value which renders tube T non-conducting, and relay R therefore becomes de-energized. When relay R becomes de-energized, valve M becomes de-energized and applies the brakes on the train. Inasmuch as the circuit for relay R includes a front contact 12 of this relay, the relay when 80 once de-energized, will remain de-energized until the path through front contact 12 is shunted. This shunting may be accomplished for example by a manually operable push button P connected in multiple with contact 12. 85 90 95 100

If contact 10 of relay S is closed when the train passes over the trackway element B, a comparatively small amount of flux from winding 2 traverses core 8, and there is substantially no change in the electro-motive force induced in winding 4. Under these conditions, then, tube T remains conducting and relay R remains energized.

The operation of relay R may be improved in some instances by connecting across its terminal an asymmetrical conductor 11. The conductor 11 shunts the relay during the alternate half cycles when no current is flowing through the tube, and in this way smooths out the pulsations in the direct current which is supplied to the relay when tube T is conducting.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a train carried tube having two spaced electrodes and a grid in a medium which forms a conducting path between said electrodes when and only when the potential between the electrodes exceeds a value which depends upon the relative potential of said grid with respect to one of said electrodes, a source of alternating current, a relay, means including said relay and a front contact of said relay for connecting said source across said electrodes, a winding on the train receiving energy from said source and connected between said grid and said one electrode for creating a difference of potential between said grid and said one electrode, means located in the trackway for at times varying the energy received by said winding from said source, and governing means on the train controlled by said relay.

2. Railway traffic controlling apparatus comprising a train carried tube having two spaced electrodes and a grid in a medium which forms a conducting path between said electrodes when and only when the potential between the electrodes exceeds a value which depends upon the relative potential of said grid with respect to one of said electrodes, a source of alternating current, a relay, means including said relay and a front contact of said relay for connecting said source across said electrodes, a first winding on the train receiving energy from said source, a second winding on the train inductively coupled with said first winding and connected between said grid and said one electrode for creating a difference of potential between said grid and said one electrode, means lo-

cated in the trackway for at times varying the coupling between said first and second windings, and governing means on the train controlled by said relay.

3: Railway traffic controlling apparatus 70 comprising a train carried tube having two spaced electrodes and a grid in a medium which forms a conducting path between said electrodes when and only when the potential between the electrodes exceeds a value which depends upon the relative potential of said grid with respect to one of said electrodes, a source of alternating current, a relay, means including said relay and a front contact of said relay for connecting said source across 75 said electrodes, a first train carried core provided with a first winding which is constantly supplied with current from said source, a second train carried core in inductive relation with said first core and provided with a second winding in which an electro-motive force is induced by the flux created by the current in said first winding, means for connecting said second winding between said grid and said one electrode, means located in the trackway for at times shunting flux away from said second core to reduce the electromotive force induced in said second winding, and governing means on the 80 train controlled by said relay.

4. Railway traffic controlling apparatus comprising a train carried tube having two spaced electrodes and a grid in a medium which forms a conducting path between said electrodes when and only when the potential between the electrodes exceeds a value which depends upon the relative potential of said grid with respect to one of said electrodes, a source of alternating current, a relay, means including said relay and a front contact of 95 said relay for connecting said source across said electrodes, a first train carried core provided with a first winding which is constantly supplied with current from said source, a second train carried core in inductive relation to said first core provided with a second winding in which an electromotive force is induced by the flux created by the current in said first winding, means for connecting said second winding between said 100 grid and said one electrode for normally creating a difference of potential between said grid and said one electrode which renders said tube conducting, a trackway inductor located adjacent the path of travel of said train carried cores in such manner that when said train carried cores are over said trackway inductor, the electromotive force induced in said second winding is at times reduced to a value which renders said tube non-conducting, a winding on said inductor provided with a circuit controlled by traffic conditions, and governing means on the train controlled by said relay.

5. Railway traffic controlling apparatus 130

comprising a train carried receiver having two windings in inductive relation, a source of alternating current connected with one said winding, a grid glow tube having two electrodes and a grid in a medium which forms a conducting path between said electrodes when and only when the potential between the electrodes exceeds a value which depends upon the potential of said grid with respect to one of said electrodes, means for connecting the other said winding between said grid and said one electrode, a train controlling circuit including a source of current and the electrodes of said tube, and trackway means for at times varying the flux from said one winding which links said other winding.

In testimony whereof I affix my signature.
